UNITED STATES PATENT OFFICE

THOMAS J. HOWLAND, OF LONG BRANCH, NEW JERSEY

BATHING CAP

Application filed December 2, 1929. Serial No. 411,103.

This invention relates to bathing caps and provides for a cap which forms a watertight seal along its edge and prevents moisture from penetrating within the interior of the cap.

A great variety of methods have been proposed for rendering bathing caps watertight but none of them have proved very satisfactory as is witnessed by the fact that bathing caps at present on the market usually consist of a simple rubber cap. A simple rubber cap is far from satisfactory and moisture generally seeps in at the edge of the cap rendering the cap totally ineffective for the purpose for which it is used.

The present invention provides a bathing cap which is adapted to form a watertight seal along the edge of the cap. This is accomplished without excessive tightening at the edge portion which would bind the head and cause discomfort to the wearer.

One of the great difficulties encountered in getting a bathing cap which will effectively keep out water is to seal the hollow or indentation between the jaw and the neck just beneath the ears. The tightening of the edge of the cap does not solve the problem as the more the edge of the cap is tightened, the greater is the tendency to draw away from the skin at this point.

In my prior Patent No. 1,746,477, granted Feb. 11th, 1930, I have shown one method of filling in these hollows, and in my application Serial No. 411,104, filed Dec. 2, 1929, a second method is shown. However, it has been found that it occasionally happens that the position of the hollow or indentation between the jaw and the neck of some persons is considerably removed from the relative position where this hollow occurs in most persons.

To provide for an effective seal between the edge of the cap and the head of the wearer where the jaw joins the neck, regardless of the particular relative position where this hollow occurs in the head of the wearer, the bathing cap of the present invention is provided with a knot or button-like member on the outside of the cap which may be adjusted to different positions in the region of

the ears to depress the edge of the cap into the hollow at those points, and thereby form a watertight seal. The knot is preferably made adjustable by having it movable along a strap secured to the outside of the cap adjacent the edge thereof.

The provision of means for depressing the edge of a bathing cap into the hollows in the region of the ears is particularly important with what is known as the straight-line bathing cap, which is contrasted with a cap having a curved contour and which fits down around the ears, necessitating the use of a chin strap. When a chin strap is used it is not so essential that the edge of the cap be depressed into the hollows in the regions of the ears, as the chin strap will tend to cause the cap to closely fit the head at these points, but with a straight-line bathing cap there is so little to hold the cap in contact with the head at the proper places, that some means for causing it to closely fit the head at these points becomes particularly important.

For an example of a bathing cap embodying my invention reference is made to the accompanying drawing in which

Figure 1 is a side elevation of the bathing cap;

Fig. 2 is a cross section taken through the rim of the cap;

Fig. 3 is an enlarged cross section taken through line 3—3 of Fig. 1;

Fig. 4 is an enlarged cross section taken through line 4—4 of Fig. 1;

Figs. 5 and 6 are views similar to Fig. 4 showing modifications;

Fig. 7 is a side view of a portion of the cap showing a further modification;

Fig. 8 is a cross section taken through line 8—8 of Fig. 7;

Fig. 9 is a view of a further modification, and

Fig. 10 shows the invention applied to a bathing shoe.

The present invention is shown as applied to a bathing cap such as is claimed in my Patent No. 1,746,477, but it is to be understood that the invention may be applied to bathing caps which are not provided with cups or air pockets along the inside of its

edge portion, or to bathing caps in which cups or air pockets are formed as shown and claimed in my application Serial No. 411,104.

The bathing cap 10 shown in the drawings is of elastic material and is what is known as a straight-line bathing cap, as the lower edge 11 is straight and is not shaped to fit the contour of the head.

Along the inside edge of the cap 10 is attached a band comprising a series of crossed ribs 12 forming cups or air pockets 13 therebetween, as is more specifically shown and described in my said Patent No. 1,746,477.

The elasticity of the material composing the cap 10 will tend to press the lower edge 11 thereof into close engagement with the head of the wearer, and the cups or air pockets by their suction effect will tend to maintain this engagement and form a watertight seal. However, due to the irregularity of the contour of the head in the region of the ears where the jaw joins the neck and forms a hollow or indentation of substantial depth, the lower edge of the cap will not bear against the head at this point. To ensure the lower edge of the cap contacting with the head at these places, I provide a pressure-exerting member in the form of a knob or button-like member 14 adjustable along a strap 15, which presses against the outer edge of the cap and depresses it into the hollows or indentations in the region of the ears.

The strap 15 is preferably made of rubber and vulcanized to the body of the cap, but if desired it may be made of other suitable material and secured to the cap in any desired manner.

The strap 15 normally lies tight against the edge of the cap so that when the button 14 is placed between it and the cap, it causes the inner side of the edge to project inwardly at that point, as is clearly shown in Fig. 3. Thus when the cap is placed upon the head of the wearer and the button 14 adjusted to a position opposite the hollow or depression where the jaw joins the neck, it will cause the edge of the cap at that point to be depressed into the hollow until it bears tightly against the head and thereby forms a watertight seal.

As shown in Figs. 1 to 4, the button is secured to the band 15 by having its outer side, that is, the side remote from the cap, made substantially C-shaped with the arms 16 of the C closing around the band 15. The button 14 may be slid along the band 15 to the desired position and when released will be frictionally retained in that position.

In Fig. 5 the button 17 has an opening therethrough near the outer edge through which the strap 15 passes.

In Fig. 6 the button 18 is grooved in its inner and outer sides as shown at 19 and 20 so that beads 21 and 22 will be formed. These beads are found sufficient to retain the

button in place between the cap and the strap 15.

In Figs. 7 and 8 the strap 23 is provided with a slot extending longitudinally thereof. The button 24 in this case is provided with a headed stud 25, which passes through a slot 23 in the band 15' and is thereby retained in adjusted position.

In Fig. 9 I have shown a button 24' which is adapted to be used in place of the button 24, shown in Figs. 7 and 8 when it is desired to provide means for varying the amount of pressure exerted at any one place. The button 24' is similar in all respects to button 24 except that the head portion which normally projects outside of the band 15' is made of the same width as the band. This provides a reversible button having heads of different thickness so that a relatively small or a relatively large pressure may be exerted at any one place, depending entirely on which head of the button is placed beneath the strap.

While the invention is particularly adapted for caps to be used upon the head of the wearer, it is intended that it may be applied to caps for covering other body members. In Fig. 10 the invention is shown as applied to a bathing shoe 26. In this case the straps 27 are positioned on each side of the edge of the upper and near the rear so that the button 28 will cause the edge of the upper to be depressed into the hollow of the foot just back of and beneath the ankle.

It will be apparent from the foregoing that I have provided a very effective means for causing a bathing cap to form a watertight seal with the body of the wearer, and while only one adjustable button has been shown for causing the edge of the cap to be depressed into one hollow or depression on each side of the head or foot, it will be obvious that additional straps and buttons could be used if it is found desirable to cause greater pressure to be exerted against the edge of the cap at any other places.

I claim:

1. A bathing cap comprising a main portion of elastic material and means adjustable peripherally along the cap for causing different portions of the edge of the cap to bear tighter against the body of the wearer at certain places than it normally would.

2. A bathing cap comprising a main portion of elastic material and means adjustable peripherally along the cap for causing different portions of the edge of the cap to bear tighter against the body of the wearer at certain places than it normally would, said adjustable means comprising a pressure-exerting member movable with respect to the main portion of the cap.

3. A bathing cap comprising a main portion of elastic material and adjustable means for causing the edge of the cap to bear tighter against the body of the wearer at certain

places than it normally would, said adjustable means comprising a pressure-exerting member movable along the outside of the cap adjacent its edge.

5 4. A bathing cap comprising a main portion of elastic material and adjustable means for causing the edge of the cap to bear tighter against the body of the wearer at certain places than it normally would, said adjustable means comprising a pressure-exerting member movable circumferentially along the outside of the cap adjacent its edge.

10 5. A bathing cap comprising a main portion of elastic material and adjustable means for causing the edge of the cap to bear tighter against the body of the wearer at certain places than it normally would, said adjustable means comprising a strap and a pressure-exerting member movable thereon along the outside of the cap adjacent its edge.

15 6. A bathing cap comprising a main portion of elastic material and adjustable means for causing the edge of the cap to bear tighter against the body of the wearer at certain places than it normally would, said adjustable means comprising a strap and a removable pressure-exerting member movable thereon along the outside of the cap adjacent its edge.

20 7. A bathing cap comprising a main portion of elastic material and adjustable means for causing the edge of the cap to bear tighter against the body of the wearer at certain places than it normally would, said adjustable means comprising a strap and a pressure-exerting member movable thereon along the outside of the cap adjacent its edge, said pressure-exerting member having arms projecting from the side adjacent the strap and engaging the strap to hold said member in adjusted position.

In testimony whereof I affix my signature.
THOMAS J. HOWLAND.
